UNITED STATES PATENT OFFICE

ANNA C. FREELAND, OF WORCESTER, MASSACHUSETTS.

DESIGN FOR A PANEL FOR CLOCK-FRONT.

SPECIFICATION forming part of Design No. 16,373, dated November 10, 1885.

Application filed August 10, 1885. Serial No. 174,072. Term of patent 3½ years.

To all whom it may concern:

Be it known that I, ANNA C. FREELAND, of the city and county of Worcester, and State of Massachusetts, have invented and produced a new and original Design for a Panel, of which the following is a specification, reference being had to the accompanying illustration, forming a part thereof, said illustration representing a front view of my aforesaid newly-10 designed panel.

My said design consists of a panel having a circular transverse opening, around which, upon the face side of said panel, are shown the representation of a church or similar tower, a portion of the main edifice adjacent to said tower, and appropriate landscape scenery as surroundings thereto, a small clock-face exposed through the opening aforesaid, a raised rim surrounding said opening, and a suitable 20 ornamental border around the outer edge of the face of the panel also constituting a part of my said design, hereinafter described more fully.

In the illustration, A represents the panel 25 proper, and B a circular transverse opening

therein, around the edge of which is the raised rim A'. Within said circular rim A' in the opening B is a small clock face, C. Around said opening and clock-face are the representation of a church or similar tower, E, a portion of the main edifice adjacent to said tower, and suitable landscape scenery as a background thereto, and around the outer edge thereof is a suitable ornamental border, F.

I claim—

The design for a panel herein shown and described, consisting of the panel A, having the circular transverse opening B, the raised rim A' around said opening, and a clock-face, C, shown within the circular rim aforesaid, 30 also having around the clock-face the representation of a church or similar tower, E, a portion of the main edifice adjacent to said tower, landscape scenery as a background thereto, and a border, F, around the outer 40 edge thereof.

ANNA C. FREELAND.
